FILLING HEAD

Carl L. Day and Frederick E. Fauth, Baltimore,
Md., assignors to Crown Cork & Seal Company,
Inc., Baltimore, Md., a corporation of New York

Application February 24, 1950, Serial No. 145,938

20 Claims. (Cl. 226—98)

1

The present invention relates to filling heads of the counterpressure type. Such heads are customarily used on filling machines for filling bottles with carbonated beverages.

In the filling of carbonated beverages, the carbonated liquid has been flowed into the bottle at a fairly slow rate to avoid foaming during liquid flow. Then, after the bottle has been filled to the proper height, it is usual to relieve or snift some of the headspace pressure to atmosphere through a small bore passage and before the bottle mouth is unsealed from the filling head for the application of a cap. The purpose of such snifting is to avoid the foaming which would result if all of the headspace pressure should be suddenly relieved to atmosphere by the movement of the mouth of the bottle from the filling head.

In order to increase the output of carbonated beverage filling machines, it is desirable to flow the liquid into the bottle at a faster rate than heretofore. It has been found that if the liquid is relatively cold, such faster flow actually does not induce as much foaming during liquid flow as might be expected. In addition, if the flow of liquid is rapid enough to complete filling the bottle to the desired height a few second before snifting is performed, the liquid reaches a state of equilibrium even if it has foamed to some extent during liquid flow.

Furthermore, permitting the liquid to "rest" before snifting minimizes the possibility of foaming either during snifting or when the bottle is subsequently released from the filling head.

An object of the invention is to provide a filling head which is of such design as to permit a maximum rate of liquid flow therethrough.

Another object of the invention is to provide a filling head of such construction that most of its elements can be machined from standard stock, rather than from special castings.

A further object is to provide a filling head including relatively simple operating means.

An additional object is to provide a filling head of such design that it will not fill bottles which would leak during filling, for example, bottles having a chipped mouth.

Other objects and advantages of the invention will be apparent from the following specification and accompanying drawings.

Referring to the drawings:

Figure 1 is an elevation of the filling head of the present invention, the view showing the filling head attached to a reservoir.

Figure 2 is an elevation showing a plurality

2

of the filling heads attached to a reservoir, the view looking toward Figure 1 from the right.

Figures 3 to 7 are axial sections through the filling head of the invention, with portions shown in elevation and other portions broken away. The five figures respectively show successive stages of operation of the filling head.

Figure 8 is a horizontal section on the line 8—8 of Figure 7.

Figure 9 is a horizontal section on the line 9—9 of Figure 7, and

Figure 10 is a fragmentary perspective view of the counterpressure gas valve.

The filling head of the present invention and its operation generally may be described as follows:

Each filling head comprises a housing 10 including an upper tubular portion 11 having a liquid chamber 12 fixed to its lower end. As is best indicated in Figures 1 and 3, the filling head may be secured to the periphery of the rotating superstructure of a filling machine by having the liquid chamber fixed to the periphery of a flange 14 extending from the centrally located filling reservoir of the filling machine. A liquid supply pipe 16 extends radially from the filling reservoir to deliver liquid, such as carbonated water or carbonated water and syrup, to the liquid chamber 12 of each filling head. The outflow of water from liquid chamber 12 is controlled by a liquid valve 18 fixed to a lower snifting tube 20 which is reciprocable centrally of housing 10. A fine mesh screen 21 extends across the outlet of chamber 12 below liquid valve 18. A spring 22 urges liquid valve 18 to raised or open position though the liquid valve will normally be in the closed position of Figure 3 by reason of the pressure of liquid acting upon the upper surface of the valve.

At its upper end, housing 10 is connected by a radial pipe 24 to a manifold 26 concentric with the filling reservoir of the machine. Manifold 26 is connected to the upper portion of the filling reservoir of the machine so that a gas pressure will exist therein corresponding to the gas pressure acting on the surface of the liquid in the reservoir.

The flow of counterpressure gas through the filling head is controlled by a counterpressure valve including a sleeve 28 which cooperates with ports and a valve seat on the upper end of snifting tube 20 as well as with a valve seat on the upper end of a counterpressure tube 30 reciprocable within snifting tube 20. Sleeve 28 depends from an upper snift tube 32 which is slidable in

the upper end of housing 10. Above housing 10 the upper snift tube 32 opens to a snift outlet line 34 which, as indicated in Figure 1, exhausts to atmosphere within the shell which surrounds the filling reservoir.

The various tubes and associated valves of the filling head are operated to predetermined vertical positions relative to housing 10 by the action of an operating lever 36 pivoted at 38 upon a collar 40 which is vertically slidable upon the exterior of housing 10. Lever 36 and collar 40 are raised and lowered with respect to housing 10 by cams such as 42a of Figure 4 and which cams are spaced about the circular path of travel of the filling heads with the rotating filling reservoir.

Referring to the general operation of the filling head, Figure 3 shows the head in closed position, viz., with operating lever 36 and operating collar 40 lowered with respect to housing 10 and with all valves in closed position so that there is no flow of either gas or liquid to or from the reservoir.

Figure 4 shows the tubes and valves in the position occupied during the counterpressure flow stage. This position is brought about by the action of a counterpressure cam 42a in raising operating lever 36 and collar 40 with respect to housing 10. As is indicated by the flow indicating arrows CP of Figure 4, counterpressure gas from the filling reservoir enters filling head by line 24 and flows downwardly in housing 10, upwardly in sleeve 28 and then downwardly through counterpressure tube 30 into a bottle. When the pressure in the bottle is balanced with that acting upon the surface of the liquid in the filling reservoir, spring 22 will raise liquid valve 18 to the position shown in Figure 5 so that liquid may now flow from the filling reservoir and liquid chamber 12 and into the bottle as indicated by the arrows L. Also, a filling cam 42b of Figure 5 will raise operating lever 36 and operating collar 40 to the position relative to housing 10 shown in Figure 5. During this liquid flow, the counterpressure gas in the bottle will be returned through the counterpressure tube 30 in a reverse direction to that followed during the counterpressure flow of Figure 4. This flow is indicated by the arrows GR of Figure 5. When the level of the liquid in the bottle covers the ports in the lower end of the counterpressure tube 30, the return flow of gas will cease and the built-up pressure beneath the screen 21 will prevent the liquid level from rising in the bottle. At about the same instant, operating lever 36 and collar 40 will be lowered by the snifting cam 42c of Figure 6 to the snifting stage position of Figure 6, thereby closing liquid valve 18 and, through a yoke 44, depressing counterpressure tube 30 and an upper snift valve 40 so that pressure in the bottle will be vented to atmosphere as indicated by the arrows S of Figure 6. Operating lever 36 and collar 40 then will be slightly lifted to the position of Figure 3 so that all passages through the filling head will be closed. If it is desired, operating lever 36 and collar 40 may be momentarily lifted to cause gas at reservoir pressure to flow through counterpressure tube 30 to blow any liquid out of that tube.

The detailed construction and operation of the filling head is hereinafter described.

The tubular portion 11 and liquid chamber 12 which comprise the filling head housing 10 have a vertical extent substantially corresponding to that of the filling reservoir. The liquid chamber

12 is soldered or welded to the lower end of the tubular portion 11 and a resilient valve seat 50 is held in the lower and open end of chamber 12 by a ring nut 51. As indicated in Figure 5, ring nut 51 includes an inwardly and downwardly extending flange 52 and the inner edge of this flange defines the outer circumference of the liquid flow stream from the filling head. Flange 52 has a downwardly facing gasket 53 suitably fixed therein. A bottle centering bell 55 of usual form and including a resilient gasket 56 to engage the mouth of a bottle has its upper and inner surface arranged to seal against the gasket 53 of liquid chamber 12. In addition, the centering bell includes a central aperture 57 of the same size as the central aperture of the ring nut flange 52. The annular space defined between the just-mentioned apertures and the outer surface of the snift tube 20 comprises the liquid discharge passage of the filling head.

As is shown in Figures 1 and 2, centering bell 55 is provided with horizontally extending lugs 60 and a rod 61 extends upwardly from each end of lug 60 and through a lateral extension 62 integral with liquid chamber 12.

Housing 10 is of tubular form and has its upper end closed by a threaded plug 64, plug 64 being centrally apertured so that upper counterpressure tube 32 is slidable therethrough. A seal is 30 maintained between plug 64 and tube 32 by means of a nut 65 bearing upon suitable packing. As has been stated above, the gas pipe 24 communicating with the filling reservoir extends radially from the upper end of housing 10.

Operating collar 40 is vertically slidable upon the exterior of housing 10. Collar 40 is fitted with an inwardly spring-pressed ball 66 adapted to engage notches 67, 68, and 69 formed in the opposed surface of the housing 10. By this arrangement, ball 66 will hold collar 40 in any vertical position to which lever 36 moves the collar. It will be observed that notch 67 is somewhat longer than the other two notches. Referring to Figure 8, it will be observed that operating lever 36 is bifurcated at one end and that pivot bolt 38 extends horizontally through the bifurcated portion and through outwardly projecting ears 70 on collar 40. The bifurcated portion of lever 36 forms two arms 71 and the free ends of these arms are adapted to bear on the upper ends of the vertical rods 61 secured to centering bell 55 whenever rods 61 are raised by reason of a bottle lifting the centering bell. At its outer end, lever 36 has a roller 73 rotatable thereon for engagement with the operating cams of the machine. A lug 74 projects outwardly from collar 40 and the upper end of a set screw 75 threaded through the lug is arranged to limit the downward swinging movement of lever 36 with respect to collar 40.

The lower snifting tube 20 of the filling head is of slightly reduced diameter below liquid valve 18 so as to increase the cross sectional area of the annular liquid discharge passage which surrounds that tube. As is illustrated in Figure 3, the lower end 75 of tube 20 is inwardly and upwardly beveled to thereby have a close fit upon a spreader 77 fixed to and surrounding the nozzle of counter-pressure tube 30. Snifting tube 20 is 65 slidable through a central aperture in screen 21. Because liquid valve 18 is secured to the snifting tube 20, the valve and tube will always move together, whether by action of operating lever 36 or spring 22.

70 Referring to Figure 5, snifting tube 20 has a

collar 80 fixed to its exterior adjacent its upper end, collar 80 being of such overall diameter that a space for gas flow will be provided between the collar and the bore of the housing 10. Above collar 80, tube 20 is of slightly reduced outside diameter and a packing ring 81 surrounds the tube and rests upon collar 80. Immediately above packing 81, a lower series of ports 82 is formed in tube 20. A second and upper series of ports 83 is formed in the tube at a point slightly spaced above the lower ports 82. Tube 20 terminates immediately above the series of ports 83 and includes a slight inwardly extending flange 84 adapted to closely engage the outer surface of counterpressure tube 30.

Counterpressure tube 30 has a nozzle 85 threaded upon its lower end. The tip 86 of nozzle 85 is of conical form to center a bottle moving upwardly about the nozzle. Adjacent its lower end nozzle 85 is provided with one or more gas ports 87. The spreader 77 is formed upon the upper end of nozzle 85 to cooperate with the beveled lower end 76 of snifting tube 20. Spreader 77 is of sufficient diameter that liquid flowing downwardly about the snifting tube 20 will be deflected outwardly to flow down along the inner wall of the mouth of a bottle.

The outside diameter of counterpressure tube 30 is such that a space for flow of counterpressure gas will be provided between that tube and the surrounding snifting tube 20. In other words, snifting flow occurs in the space between the tubes 20 and 30. The bore of counterpressure tube 30 is of adequate diameter to permit the necessary flow of counterpressure gas. As best shown in Figure 10, the upper edge of counterpressure tube 30 is belled to provide an upwardly facing annular seat 90. A spring 91 surrounds tube 30 between the undersurface of the belled seat 90 and the upper flange 84 of snifting tube 20. Spring 91 thereby urges counterpressure tube 30 upwardly with respect to snifting tube 20 whenever tube 30 is free for such upward movement.

The sleeve 28 which, with the upper ends of the tubes 20 and 30 forms the counterpressure gas controlling valve, is of sufficient inside diameter that a space will be provided therein and outwardly of the counterpressure tube 30 for flow of gas. The outside diameter of sleeve 28 is such that a space for gas flow will be provided outside the sleeve and within housing 10. The lower end of sleeve 28 (Figure 10) is inwardly flanged as indicated at 95, the inner edge of the flange having a close fit against the outer surface of the upper end of lower snifting tube 20. Flange 95 is of such axial extent that when sleeve 28 is in the lowered position indicated in Figure 3, the flange will completely cover the lower series of ports 82. The series of ports 82 and 83 are spaced by such distance axially of tube 20 that flange 95 may be positioned between both series of ports without restricting ports of either series.

The upper snifting tube 32 has its lower end enlarged as indicated at 97 and the enlargement has a sealed connection with the upper end of the sleeve 28. The extreme lower end of upper snifting tube 32 is within sleeve 28 and of less diameter than the inner surface of the sleeve 28. Radial ports 98 provided in this portion of tube 32 open to the interior of sleeve 28 and to the bore of tube 32. The lower end of the bore of tube 32 is closed by a valve disk 100 of resilient material which controls flow to and from the

upper end of counterpressure tube 30. As has been stated above, the upper snifting tube 32 is axially movable through the packed aperture in plug 64 which closes the upper end of housing 10. Above housing 10, upper snifting tube 32 is threadedly connected to a fitting 102 extending upwardly from the tube. The extreme upper end of tube 32 may have an apertured sleeve 103 fitted therein to restrict the flow of gas and also to center the lower end of a spring 104 fitted within a bore 105 of fitting 102. A valve 106 is mounted in the upper end of spring 104, the valve being of piston type to include a reduced central portion indicated at 107. As is best indicated in Figure 3, the reduced portion 107 of valve 106 will be positioned opposite the mouth of snift exhaust pipe 34 when valve 106 is held closed by spring 104. As is hereinafter explained, spring 104 is of greater strength than the spring 91 which urges counterpressure tube 30 upwardly.

The fitting 102 has a slot or eye 110 extending diametrically through its upper portion and the bight of yoke 44 extends through this slot. As is hereinafter explained, when lifting action is exerted upon yoke 44 by the operating collar 40, fitting 102, upper snift tube 32 and sleeve 28 will be lifted. When yoke 44 is lowered to an intermediate position, the valve disk 100 will close the upper end of counterpressure tube 30 and the lower end of sleeve 28 will be in sealed engagement with the packing 81 on snift tube 20. Still further downward movement of yoke 44 will bring the bight of the yoke into engagement with the upper snift valve 46 to depress that valve and permit flow from upper snift tube 32 to the snift exhaust pipe 34.

Operation

As has been indicated above, a series of filling heads of the present invention would be connected to the filling tank or reservoir of a rotary bottle filling machine by means of liquid lines 16 extending from the lower and liquid containing portion of the reservoir to the liquid chamber 12 of each filling head. A gas line extends from the upper or gas containing portion of the reservoir to the gas manifold 26 which, in turn, is connected to the upper portion of each filling head housing 10. The filling reservoir would be of any well-known counterpressure type adapted to maintain liquid at a substantially constant level therein and with a substantially constant pressure of gas above the liquid.

Close stage (preliminary)

Figure 3 illustrates the filling head with the parts in the position they would occupy when the filling head is closed. The head will be in this stage during the interval after a bottle or other container has been moved downwardly from the head and the head is moving with the filling reservoir to a position to receive an unfilled bottle. Therefore, the centering bell 55 will be in the lowered and dotted line position of Figure 1 and the stop collars 63 adjacent the upper ends of the centering bell rods 61 will bear upon the top surface of the fitting 62 in which the liquid chamber 12 is formed.

When a syruped or an empty bottle moves upwardly toward the filling head, the inclined inner surface of the centering bell will tend to center the bottle with respect to nozzle 85 before the mouth of the bottle comes into engagement with the sealing ring 56. The conical lower end 86

of the counterpressure tube 30 will also have a centering action with respect to the bottle. When the bottle has lifted the centering bell 55 into sealed relation against the packing ring 53, the bottle and filling head will be in sealed relation. As is shown by solid lines in Figure 1, the upper ends of the rods 61 will now be in contact with the arms 71 of operating lever 36, though the operating lever will still rest upon the stop bolt 75.

Counterpressure flow stage

With the bottle now sealed to the filling head, the rotation of the filling reservoir and filling table will bring the roller 73 of operating lever 36 into engagement with the counterpressure cam 42a, thereby lifting the arm from the position illustrated in Figures 1 and 3 to the position illustrated in Figure 4. Because the arms 71 of lever 36 are bearing upon the upper ends of the centering bell rods 61, the rods will serve as a fulcrum for lever 36. Therefore, the upward swinging of lever 36 will cause sleeve 40 to move upwardly along the housing 10 to such an extent that ball 66 will move out of the notch 67 and into engagement with the notch 68 of housing 10. The spring-pressed ball will hold sleeve 40 in this elevated position even if cam 42a does not extend along the full path of travel of the filling head during the counterpressure flow stage.

It will be observed that because the rods 61 fixed to the centering bell 55 serve as the fulcrum for lever 36, the filling head will not be operated if no bottle is lifted to the filling head upon a container supporting platform. In other words, if the filling head fails to receive a bottle, the centering bell 55 and rods 61 will remain in the lowered position indicated by dotted lines in Figure 1. Therefore, even though the operating rod 36 subsequently contacts with the various operating cams such as 42a, these cams will simply swing lever 36 about its pivot 38 and no lifting action will be exerted upon sleeve 40.

The lifting of operating sleeve 40 to the position of Figure 4 causes yoke 44 to also lift, with the result that the bight of the yoke will exert a lifting action in the eye 110 of the snift tube fitting 102. Hence, upper snift tube 32 and sleeve 28 will thereby be lifted so that the lower edge 95 of sleeve 28 will move away from the sealing ring 81 and upwardly along lower snifting tube 20 to a point between the upper and lower ports 82 and 83. The lifting of sleeve 28 will also move valve disk 100 out of engagement with the seat 90 at the upper end of counterpressure tube 30. During the lifting of valve disk 100, spring 91 will also lift the counterpressure tube 30 with respect to lower snift tube 20 until the spreader 71 on the counterpressure tube nozzle contacts with the lower edge 16 of lower snift tube 20. The snift tube will not lift because of the pressure of liquid in the reservoir and housing 10 acting upon the upper surface of the liquid valve 18. The level of the liquid is indicated in Figures 3 to 7 and counterpressure gas will be present above this level in both housing 10 and the filling reservoir.

As soon as sleeve 28 uncovers the ports 82, and when it thereafter reaches the position shown in Figure 4, gas will flow through the lower port 82 of snift tube 20 to fill that tube. However, the lifting of spreader 71 prevents outflow of any gas from the lower end of the snift tube. Instead, counterpressure gas will flow out of the snifting tube by the upper ports 83 and, as shown

5 by the arrows CP of Figure 4, upwardly in sleeve 28 and downwardly into the upper end of counterpressure tube 30 and thence into the bottle. Because the upper snift valve 106 is closed, gas cannot escape to atmosphere through the upper snift tube 32.

10 As is usual, the counterpressure stage will be very brief because it will require only a short interval of time for the flow of gas into the bottle from housing 10 and the filling reservoir to bring the bottle to the same pressure as exists above the liquid in the reservoir. The fact that counterpressure exists in housing 10 outwardly of sleeve 28 shortens the path of counterpressure flow and 15 further expedites establishment of counterpressure in the bottle.

Filling stage

20 When counterpressure has been established in the bottle, the pressure acting on the upper and lower sides of liquid valve 18 will be balanced and spring 22 will lift valve 18 so that liquid will flow downwardly into the bottle through the liquid outlet of chamber 12, viz., the annular space 25 surrounding the snifting tube 20 and bounded by the central port in ring-nut 51. Because this space is of maximum cross-section, the flow of liquid will be rapid. The flow of liquid is indicated by the arrows L of Figure 5.

30 At about the same moment that counterpressure is established in the bottle, the operating arm 36 will come into contact with a second or filling cam 42b which is slightly higher than cam 42a. Therefore, as shown in Figure 5, arm 36 will 35 swing further upwardly with respect to the fulcrum rods 61 so that operating sleeve 40 will correspondingly rise to position the spring-pressed ball 66 in the uppermost notch 69 of housing 10.

36 The just-mentioned further lifting of operating sleeve 40 will cause yoke 44 to further lift the snift valve fitting 102, upper snift tube 32 and sleeve 28 to compensate for the lifting of snift tube 20 occasioned by the lifting of the liquid valve 18. In other words, the lifting of the liquid valve 18 by spring 22 which occurs when the pressure in the bottle is balanced with the pressure in the filling reservoir will result in carrying the snift tube 20 upwardly to a point where its lower ports 82 will be opposite the lower edge 45 95 of sleeve 28. With snift tube 20 in this position relative to the edge 95 of sleeve 28, the counterpressure passage would be closed. Hence, the just-mentioned further lifting of sleeve 28 is 50 necessary to maintain the lower edge 95 of that 55 sleeve between the ports 82 and 83 of the snift tube. It will be understood that the filling cam 42b readily can be positioned to further lift sleeve 28 at the instant liquid valve 18 lifts.

56 With the elements of the filling head in the position illustrated in Figure 5, during the flow of liquid into the bottle, the counterpressure gas in the bottle will flow (as shown by the arrows GR) through the ports 87 in nozzle 85, upwardly in counterpressure tube 30 to the interior of sleeve 28, and thence through the ports 83 and 82 of snifting tube 20 to housing 10 and gas line 24 leading to the reservoir. The flow of liquid into the bottle and flow of gas from the bottle will 60 continue until the liquid covers the ports 87 so that no more gas can escape from the bottle. However, the liquid will rise slightly above this point by reason of the head of liquid in the filling reservoir. The gas in the bottle headspace above the level of the liquid will thereby be compressed 65 to such an extent that little, if any, additional 70 75

liquid ordinarily can flow downwardly through screen 21. At any rate, such additional liquid as may flow into the bottle will result in upward movement of liquid into counterpressure tube 30. That is, screen 21 is of sufficiently fine mesh that with the headspace gas at increased pressure, surface tension of the liquid, or possibly capillarity, will prevent downward flow of liquid as well as upward escape of gas.

Leaking bottle

In the event that a bottle leaks counterpressure for any reason, usually by reason of a chip in the mouth of the bottle, counterpressure will not be established in the bottle during the counterpressure flow stage. Therefore, the pressure in the bottle will not be balanced with the pressure above the liquid in the filling reservoir and filling valve 18 will not open. As has been stated above, with a normal bottle, sleeve 28 is given a second upward movement by filling cam 42b to compensate for the lifting of snift tube 20 with liquid valve 18 to thereby maintain the counterpressure flow passage open for return flow to the filling reservoir. However, if liquid valve 18 fails to rise because of the leak of pressure from the bottle, lower snift tube 20 will not rise, but will remain in the position it occupied in the closed and counterpressure stages. Therefore, and as shown in Figure 7, when sleeve 28 is given a second lift by filling cam 42b, the lower edge 95 of sleeve 28 will be brought opposite the upper ports 83 of lower snift tube 20. This will result in closing the counterpressure flow path and prevent further flow of gas from the filling reservoir into the leaking bottle. If such flow of counterpressure could continue throughout the length of travel of the bottle during the filling stage, a waste of gas from the filling reservoir would occur, with resultant unbalancing of conditions within the reservoir.

Snifting stage

A short time after the liquid in the bottle covers the port 87 in the lower end of counterpressure tube 30, or very shortly thereafter, operating lever 36 will come in contact with a downwardly facing snift cam 42c. The duration of the interval between the moment liquid covers the ports 87 and the contact of lever 36 with snift cam 42c will depend upon how long the liquid is to rest before snifting occurs. Cam 42c will move operating lever 36 to the position illustrated in Figure 6 by first swinging lever 36 downwardly on its pivot 38 until it contacts with stop 75 and then further forcing the lever bodily downward to such an extent that operating sleeve 40 will move downwardly to bring ball 66 to the lower portion of the lowermost and longer notch 67 of housing 10.

The above-mentioned downward movement of sleeve 40 will cause yoke 44 to come into contact with the upper end of the upper snift valve 46. However, the spring 104 which holds valve 46 upwardly and seated is of sufficient strength that valve 46 will not be opened at this time. Instead, snift fitting 102 will move downwardly with upper snift tube 32 to thereby move the sleeve downwardly along lower snift tube 20 until the lower edge 95 of sleeve 28 comes into contact with packing ring 81 and valve disk 100 contacts with the upper seat end 90 of counterpressure tube 30. Then spring 91 will be compressed so that sleeve 28 will continue to move downwardly and exert force on lower snift tube 20 against spring 22 so that liquid valve 18 will close. Counter-pres-

sure tube 30 can move further downwardly than lower snift tube 20 and, therefore, tube 30 will carry spreader 77 down and out of contact with the lower end of lower snift tube 20. Thus the lower end of the snift tube will be open to the headspace of the bottle.

With liquid valve 18 in contact with its seat 50 to limit further downward movement of lower snift tube 20, and with the lower end of sleeve 10 28 in firm contact with ring 81 on tube 20, further downward movement of sleeve 28 and upper snift tube 32 will be prevented. Therefore, the final downward movement of yoke 44 with operating sleeve 40 will be applied against the relatively strong spring 104 which has heretofore held upper snift valve 46 upward in seated position. When valve 106 is thus opened, the headspace pressure in the bottle will be relieved as shown by the arrows S of Figure 6, i. e., through the lower snift valve formed by spreader 77 and the bottom edge 76 of lower snift tube 20, upwardly through tube 20 into sleeve 28 and thence by the ports 83 into upper snift tube 32. From tube 32 the snifted gas will move past upper snift 25 valve 46 and into the exhaust tube 34 which opens to atmosphere.

It will be understood that the snifting stage is extremely brief as compared to the filling stage.

Closed stage (final)

At the completion of the snifting stage, operating lever 36 will contact with an upwardly facing cam 42d which will lift the lever 36 to the position of Figure 3, thereby raising operating sleeve 40 sufficiently to bring the ball 66 into the upper portion of the lower notch 67. This will lift yoke 44 enough to permit valve spring 104 to close upper snift valve 46. Hence, all of the flow passages through the filling head will be closed. The fact that spreader 77 is still out of engagement with the lower edge of the snift tube 20 cannot result in snifting flow to atmosphere because of the closing of the upper snift valve 46.

With the filling head passages closed, the filled bottle will be moved downwardly from the filling head. The centering bell 55 will thereby drop to the lowered position indicated by dotted lines in Figure 1.

As has been stated above, some liquid may move upwardly into the counterpressure tube 30 during the latter portion of the filling stage. It is frequently desirable to eject such liquid from the tube before a fresh bottle is placed beneath the filling head. If such blow-out is desired, an upwardly facing cam will be provided upon the machine between the closing cam 42d and the counterpressure cam 42a. More particularly, the blow-out cam will be positioned in that portion of the path of travel of a filling head during which no bottle is positioned below the filling head. The blow-out cam must be of sufficient height to raise sleeve 40 even though the fulcrum rods 61 are out of the path of movement of lever 36. That is, the cam preferably will be high enough to lift the outer portion of lever 36 sufficiently that it will contact with the boss 66a in which ball 66 is mounted. When this contact occurs, sleeve 40 will be bodily lifted enough to very slightly raise the lower edge 95 of sleeve 28 out of contact with packing ring 81. This slight opening of the ports 83 will permit pressure to flow from the filling reservoir in the same path as described above for the counterpressure flow stage. As a result, all liquid will be

blown from counterpressure tube 30 through the ports 87.

The lifting of operating sleeve 49 during blow-out need not be sufficient to bring the ball 66 into engagement with the intermediate notch 68. Therefore, when the operating arm 36 moves off the blow-out cam, operating sleeve 40 will drop by its own weight to the closed position of Figure 3. Alternatively, an additional cam can be provided to lower sleeve 49 to the Figure 3 position.

It will be observed that the filling head of the present invention permits rapid flow of water into a bottle so that the filling stage will require a minimum period of time. Advantage can be taken of this fact to permit the liquid in the bottle to become quiescent before snifing occurs. In other words, the snifing cam 42c may be so positioned upon the machine that operating lever 36 will not contact therewith for a brief period after the liquid in the bottle has covered the ports 87.

The filling head disclosed herein is of such form that almost all the elements thereof can be formed of tubular stock. This reduces the cost of material as well as the cost of machining the various parts. In addition, the filling head is of such design that leaking bottles will not be filled.

It will also be observed that the two snift tubes 29 and 32, with sleeve 28, serve to close counterpressure tube from housing 10 and that sleeve 28 serves as a path for both counterpressure as well as snifted gases. These arrangements substantially simplify the valve structure required for a counterpressure filling operation.

The terminology used in the specification is for the purpose of description and not of limitation, the scope of the invention being indicated in the following claims.

We claim:

1. A filling head for counterpressure fillers comprising a housing including a lower liquid inlet and an upper gas port respectively adapted to be connected to the liquid and counterpressure gas containing portions of a filling reservoir to provide a liquid containing portion and a superposed counterpressure portion in said housing, a vertical counterpressure tube extending downwardly from the counterpressure containing portion of said housing and having a nozzle positioned below said housing, a liquid outlet port in the lower end of said housing and surrounding said counterpressure tube, a lower snift tube surrounding said counterpressure tube, a valve fixed to said lower snift tube to control the liquid outlet port of said housing, an upper snift tube coaxial with and spaced above said counterpressure and lower snift tubes, a sleeve depending from said upper snift tube and enclosing the upper end of said counterpressure tube, said sleeve and said counterpressure tube respectively being provided with cooperating valve elements forming a valve to control flow through said counterpressure tube.

2. A filling head for counterpressure fillers comprising a housing including a lower liquid inlet and an upper gas port respectively adapted to be connected to the liquid and counterpressure gas containing portions of a filling reservoir to provide a liquid containing portion and a superposed counterpressure portion in said housing, a vertical counterpressure tube extending downwardly from the counterpressure containing portion of said housing and having a nozzle positioned below said housing, a liquid outlet port in the lower end of said housing and surrounding said counterpressure tube, a lower snift tube surrounding said counterpressure tube, a valve fixed to said lower snift tube to control the liquid outlet port of said housing, an upper snift tube coaxial with and spaced above said counterpressure and lower snift tubes, a sleeve depending from said upper snift tube and enclosing the upper end of said counterpressure tube, said lower and upper snift tubes being movable relative to each other to form counterpressure supply, counterpressure return, and snift passages.

said counterpressure tube, a lower snift tube surrounding said counterpressure tube, a valve fixed to said lower snift tube to control the liquid outlet port of said housing, an upper snift tube coaxial with and spaced above said counterpressure and lower snift tubes, a sleeve depending from said upper snift tube and enclosing the upper end of said counterpressure tube, said sleeve and said counterpressure tube respectively being provided with cooperating valve elements forming a valve to control flow through said counterpressure tube, and said sleeve and said lower snift tube respectively being provided with cooperating valve elements to form a second valve to control flow through said counterpressure tube.

3. A filling head of the character described in claim 2 wherein said two counterpressure valves are independently operable.

4. A filling head of the character described in claim 2 wherein said second counterpressure controlling valve comprises a movable valve element on said sleeve, and a seat and superposed and vertically spaced ports on said lower snift tube.

5. A filling head of the character described in claim 2 including a spring to normally hold said first counterpressure valve closed, a second spring to hold said liquid outlet valve open, a snift valve in said upper snift tube, and means operable to lift said sleeve to open said counterpressure valve, lower all of said tubes to close both said counterpressure valves and said liquid valve and then open said snift valve.

6. A filling head of the character described in claim 5 wherein said springs to hold said first counterpressure valve closed and said liquid outlet valve open are relatively light, and including a relatively strong spring to normally hold said snift valve closed.

7. A filling head of the character described in claim 5 wherein said springs to hold said first counterpressure valve closed and said liquid outlet valve open are relatively light, said actuating means comprises a member vertically movable of said housing and alternately engageable with said upper snift tube and said snift valve, and including a relatively strong spring to normally hold said snift valve closed against opening thereof by said actuating means.

8. A filling head for counterpressure fillers comprising a housing including a lower liquid inlet and an upper gas port respectively adapted to be connected to the liquid and counterpressure gas containing portions of a filling reservoir to provide a liquid containing portion and a superposed counterpressure portion in said housing, a vertical counterpressure tube extending downwardly from the counterpressure containing portion of said housing and having a nozzle positioned below said housing, a liquid outlet port in the lower end of said housing and surrounding said counterpressure tube, a lower snift tube surrounding said counterpressure tube, a valve fixed to said lower snift tube to control the liquid outlet port of said housing, an upper snift tube coaxial with and spaced above said counterpressure and lower snift tubes, a sleeve depending from said upper snift tube and enclosing the upper end of said counterpressure tube, said lower and upper snift tubes being movable relative to each other to form counterpressure supply, counterpressure return, and snift passages.

9. A filling head for counterpressure fillers comprising a housing including a lower liquid

75

inlet and an upper gas port respectively adapted to be connected to the liquid and counterpressure gas containing portions of a filling reservoir to provide a liquid containing portion and a superposed counterpressure portion in said housing, a vertical counterpressure tube extending downwardly from the counterpressure containing portion of said housing and having a nozzle positioned below said housing, a liquid outlet port in the lower end of said housing and surrounding said counterpressure tube, a lower snift tube surrounding said counterpressure tube, a valve fixed to said lower snift tube to control the liquid outlet port of said housing, an upper snift tube coaxial with and spaced above said counterpressure and lower snift tubes, a sleeve depending from said upper snift tube and enclosing the upper end of said counterpressure tube, said lower and upper snift tubes being movable relative to each other to form counterpressure supply, counterpressure return, and snift passages through said sleeve.

10. A filling head for counterpressure fillers comprising a tubular housing adapted to be secured to a filling reservoir, said housing including a liquid inlet port at its lower portion for connection to the liquid containing area of the reservoir and a gas port at its upper portion for connection to the gas containing area of the reservoir, a counterpressure tube within said housing, a nozzle on the lower end of said tube to extend into a container to be filled, a lower snift tube surrounding said counterpressure tube, said counterpressure tube having a circular seat formed thereon and spaced above its lower end and against which the lower end of said lower snift tube normally seats, said tubular housing being provided with a liquid outlet port at its lower end and in communication with the liquid inlet port of the housing, a liquid outlet valve fixed to and surrounding said lower snift tube, a spring to urge said liquid valve and lower snift tube upwardly to open position of said liquid valve, the upper end of said lower snift tube being provided with upper and lower apertures, an upper snift tube in said housing coaxial with said counterpressure and lower snift tubes, said upper snift tube including a depending sleeve normally enclosing the apertures in said lower snift tube, an upwardly facing valve seat surrounding the upper end of said lower snift tube, the lower end of said sleeve being adapted to seal against said seat and have sealing engagement with the exterior wall of said lower snift tube, a second valve in said sleeve to normally close the upper end of said counterpressure tube, said upper snift tube including a port opening to atmosphere, a third valve normally closing said upper snift tube port, actuating means operable to raise said sleeve to a position wherein the lower end of said sleeve will be intermediate the upper and lower apertures of said lower snift tube and the valve of said sleeve will be raised from the upper end of said counterpressure tube to thereby place the housing gas port in communication with the nozzle of said counterpressure tube; means to lift said liquid valve and counterpressure tube to open said liquid outlet port when the pressure in a container increases to a predetermined value, said actuating means being thereafter operable to lower said sleeve and open said third valve.

11. A filling head of the character described in claim 10 including a fitting at the upper end of said upper snift tube, said fitting being provided

with a vertical slot into the lower end of which said snift valve upwardly projects, and wherein said actuating means comprises a member vertically movable with respect to said housing and adapted to alternately engage the upper end of said slot or said snift valve.

12. A filling head for counterpressure fillers comprising a housing including a lower liquid inlet and an upper gas port respectively adapted to be connected to the liquid and counterpressure gas containing portions of a filling reservoir to provide a liquid containing portion and a superposed counterpressure portion in said housing, a vertical counterpressure tube extending downwardly from the counterpressure containing portion of said housing and having an outlet below said housing, a lower vertical snift tube having an inlet above the outlet of said counterpressure tube, a liquid outlet in said housing surrounding said tubes, a liquid outlet valve fixed to said lower snift tube and normally closing the liquid outlet of said housing, an upper snift tube positioned in the counterpressure portion of said housing and including a depending sleeve extending about the upper end of said counterpressure tube, said lower snift tube normally contacting said sleeve to close the upper end of said counterpressure tube from the counterpressure portion of said housing, said two snift tubes normally being in flow communication with each other, a normally closed snift valve to atmosphere in said upper snift tube, actuating means to first raise said sleeve out of contact with said lower snift tube, means acting simultaneously with said actuating means to raise said counterpressure tube by a lesser distance, means to raise said lower snift tube and liquid outlet valve when pressure in a bottle being filled is balanced with the pressure in the counterpressure portion of said housing, said actuating means then being operable to raise said sleeve a further distance with respect to the lower snift tube to permit counterpressure flow from said counterpressure tube to said housing, and thereafter lower all of said tubes to normal position and open said snift valve.

13. A filling head for counterpressure fillers comprising a housing adapted to be fixed to the periphery of a filling reservoir rotatable with and above vertically reciprocable container supporting platforms, a flow nozzle depending from said housing, reciprocable valve elements in said housing to control flow of liquid and counterpressure, a container centering bell, a rod fixed to said bell and vertically reciprocable in said housing, an operating lever for said valve elements pivoted with respect to said housing on a horizontal axis, said rod and lever being free of each other when the bell is in lowered position, said rod being of such vertical length as to serve as a fulcrum for said lever when the rod is raised with said centering bell.

14. A filling head of the character described in claim 13 wherein said operating lever is pivoted upon a sleeve vertically reciprocable with respect to said housing.

15. A filling head of the character described in claim 13 wherein said operating lever is pivoted upon a sleeve vertically reciprocable with respect to said housing, and means is provided to hold said sleeve stationary upon said housing in positions to which said lever may operate the sleeve.

16. A filling head for counterpressure fillers comprising a housing including a lower liquid

inlet and an upper gas port respectively adapted to be connected to the liquid and counterpressure gas containing portions of a filling reservoir to provide a liquid containing portion and a superposed counterpressure portion in said housing, a vertical counterpressure tube extending downwardly from the counterpressure containing portion of said housing and having a nozzle positioned below said housing a liquid outlet passage in the lower end of said housing and alongside said counterpressure tube, a valve to control flow through said counterpressure tube, a valve to control flow through said liquid passage, and a snift tube structure coaxial with and surrounding said counterpressure tube, said liquid flow controlling valve being fixed to said snift tube.

17. A filling head for counterpressure fillers comprising a housing including a lower liquid inlet and an upper gas port respectively adapted to be connected to the liquid and counterpressure gas containing portions of a filling reservoir to provide a liquid containing portion and a superposed counterpressure portion in said housing, a vertical counterpressure tube extending downwardly from the counterpressure containing portion of said housing and having a nozzle positioned below said housing a liquid outlet passage in the lower end of said housing and alongside said counterpressure tube, a valve to control flow through said counterpressure tube, a valve to control flow through said liquid passage, a snift tube structure coaxial with and surrounding said counterpressure tube, said liquid flow controlling valve being fixed to said snift tube, and a valve to control flow through said snift tube.

18. A filling head for counterpressure fillers comprising a housing including a lower liquid inlet and an upper gas port respectively adapted to be connected to the liquid and counterpressure gas containing portions of a filling reservoir to provide a liquid containing portion and a superposed counterpressure portion in said housing, a vertical counterpressure tube extending downwardly from the counterpressure containing portion of said housing and having a nozzle positioned below said housing, a liquid outlet passage in the lower end of said housing and alongside said counterpressure tube, a valve to control flow through said counterpressure tube, a valve to control flow through said liquid passage, and a snift tube structure coaxial with and at least a portion of which surrounds said counterpressure tube, said tubes being axially movable relative to each other and respectively being provided with cooperating valve elements forming valve devices to control flow through said tubes.

19. A filling head for counterpressure fillers comprising a housing including a lower liquid inlet and an upper gas port respectively adapted

to be connected to the liquid and counterpressure gas containing portions of a filling reservoir to provide a liquid containing portion and a superposed counterpressure portion in said housing, a vertical counterpressure tube extending downwardly from the counterpressure containing portion of said housing and having a nozzle positioned below said housing, a liquid outlet passage in the lower end of said housing and alongside said counterpressure tube, a valve to control flow through said counterpressure tube, a valve to control flow through said liquid passage, and a snift tube structure coaxial with and at least a portion of which surrounds said counterpressure tube, said tubes being axially movable relative to each other and respectively being provided with cooperating valve elements forming valve devices to control flow through said tubes, the valve devices to control flow through said snift tube being arranged in tandem.

20. A filling head for counterpressure fillers comprising a housing including a lower liquid inlet and an upper gas port respectively adapted to be connected to the liquid and counterpressure gas containing portions of a filling reservoir to provide a liquid containing portion and a superposed counterpressure portion in said housing, a vertical counterpressure tube extending downwardly from the counterpressure containing portion of said housing and having a nozzle positioned below said housing, a liquid outlet passage in the lower end of said housing and alongside said counterpressure tube, a valve to control flow through said counterpressure tube, a valve to control flow through said liquid passage, and a snift tube structure coaxial with and at least a portion of which surrounds said counterpressure tube, said tubes being axially movable relative to each other and respectively being provided with cooperating valve elements forming valve devices to control flow through said tubes, the valve devices to control flow through said snift tube being arranged in tandem, means being provided to prevent operation of one of the snift tube valve devices to open position until after the counterpressure valve device has been closed.
